BY

Arthur M. Berger ATTORNEY

UNITED STATES PATENT OFFICE

131,980

DESIGN FOR A UNIFORM

Arthur M. Berger, New York, N. Y.

Application February 18, 1942, Serial No. 105,866

Term of patent 3½ years

To all whom it may concern:

Be it known that I, Arthur M. Berger, a citizen of the United States of America, residing in the Borough of Manhattan, county of New York and State of New York, have invented a new, original, and ornamental Design for a Uniform, of which the following is a specification, reference being had to the accompanying drawing, forming part thereof.

Fig. 1 is a front view of a uniform showing my new design.

Fig. 2 is a rear view thereof.

I claim:

The ornamental design for a uniform substantially as shown.

ARTHUR M. BERGER.
